UNITED STATES PATENT OFFICE.

WALTER R. SCHLAGE, OF SAN FRANCISCO, CALIFORNIA.

DOORKNOB FASTENER.

Application filed August 2, 1923. Serial No. 655,219.

This invention relates to a door knob fastener and especially to means for locking a door knob against endwise and turning movement with relation to the spindle upon which it is mounted.

The object of the present invention is to generally improve and simplify the construction and operation of fasteners of the character described; to provide a knob fastener which is carried by the spindle and which is automatically projected into locking engagement with relation to the knob when this is applied; a knob fastener which secures the knob both against endwise and turning movement with relation to the spindle, and furthermore a fastener which cannot work loose or become lost, and which may be manually released when it is necessary to remove the knob, for instance, when repairing the lock, or otherwise. Other objects will hereinafter appear.

One form which my invention may assume is exemplified in the following description and illustrated in the accompanying drawings, in which—

Fig. 1 is a central, longitudinal section of a door knob, and the spindle upon which it is mounted, said figure also illustrating the fastening mechanism employed.

Fig. 2 is a cross section on line 2—2, Fig. 1.

Fig. 3 is a cross section on line 3—3, Fig. 1.

Fig. 4 is a plan view of a portion of the spindle showing the depressed portion in which the fastener actuating spring is mounted.

Referring to the drawings in detail, and particularly to Fig. 1, 1 indicates an ordinary door knob, 2 the sleeve or shank of the same, and 3 the spindle upon which the knob is mounted. A tubular spindle is in this instance illustrated and the object of the invention is to secure the knob on the spindle both against endwise and turning movement with relation thereto. Furthermore, to provide a fastener which is automatically projected into locking engagement when the knob is applied and which may be manually depressed to release the knob if it is necessary to remove the same. This is accomplished in the following manner:

The spindle, which in this instance is tubular, is first slotted transversely as indicated at 4. A round hole is then drilled or punched a distance therefrom as shown at 5, and the intermediate portion 6 is then depressed by means of a die or the like to form

a segmental or half round channel 7 which tapers from end to end; the widest portion being presented towards the punched portion 5.

The fastener proper indicated at 8, and which is perhaps best illustrated in Figs. 1 and 3, consists of a flat rectangular-shaped plate, the lower portion of which is provided with two lugs 9 between which is formed a V-shaped recess 10. The plate is slidably mounted in the slot 4 and is guided by the enlarged end of the depressed portion 6 on one side and by the rounded wall of the spindle shown at 11 on the opposite side. The plate is vertically movable in the slot 4 and it is normally held in raised or projected position by means of a spring 12. This spring may be flat or as here illustrated is preferably constructed of round spring wire. One end of the spring is inserted through the punched portion 5 as indicated at 13, and it is then bent over the upper portion of the depressed member 6 as indicated at 14; this portion forming a support or fulcrum for the spring which tends to force the opposite end 15 in an upward direction. This end passes under the plate 8 and is centered with relation thereto by the lugs 9 and the V-shaped recess 10, the wire being sufficiently long to project beyond the plate and in under the rounded shoulder of the spindle shown at 16.

The spring serves three functions, first, that of normally projecting the plate; secondly, that of forming a stop which limits upward movement of the plate by engaging the shoulder 16, and, third, that of forming a stop which limits downward movement of the plate by engaging the lower portion of the member 6.

The shank 2 of the knob is slotted as indicated at 17 to receive the upper end of the plate, the locking plate when projecting through the slot serving the function of locking the knob and shank against endwise movement on the spindle. It also serves the function of locking the knob and shank against turning movement, but the plate is not entirely depended upon for this purpose as a key is formed in the opposite end of the shank as indicated at 18 which projects into a longitudinal key-way 19 formed in the spindle. The key and the key-way thus secure the knob and shank against turning movement, while the plate 8 secures the knob and shank against endwise movement.

The fastener here illustrated is exceedingly simple in construction and will not be accidentally displaced or released by turning movement of the knob, vibration or otherwise, as the plate is always held in projected position by the tension of the spring 12 imposed thereon. For instance, most door knobs are secured to the spindles by means of ordinary set screws. These screws 10 work loose and drop out, thus leaving the knob free to be removed. This objection is entirely overcome by the present structure. The fastener may furthermore be manually depressed and it is therefore possible 15 to remove the knob if the lock is to be repaired, inspected or otherwise.

While certain features of the present invention are more or less specifically illustrated, I wish it understood that various 20 changes in form and proportion may be resorted to within the scope of the appended claims; similarly, that the materials and finish of the several parts employed may be such as the experience and judgment of 25 the manufacturer may dictate or various uses may demand.

Having thus described my invention, what I claim and desire to secure by Letters Patent is—

- 30 1. A device of the character described, comprising a tubular spindle having a slot formed therein transversely of the longitudinal axis of the spindle, a radially movable locking plate carried by the spindle and guided in the slot, a knob adapted to be received by the spindle, said knob having a slot formed therein adapted to register with the slot in the spindle, and a spring disposed longitudinally of the tubular spindle and 35 interiorly thereof and adapted to force the locking plate radially outward through

the spindle and into the slot in the knob to secure the knob.

2. A device of the character described, comprising a tubular spindle having a slot 45 formed therein disposed transversely of the longitudinal axis of the spindle, a radially movable locking plate interior of the spindle and guided in the slot, a knob, a shank on the knob adapted to be received by the 50 spindle, said shank having a slot formed therein adapted to register with the slot in the spindle, a spring interiorly tubular of the spindle engaging the locking plate and exerting a pressure to project the locking 55 plate into the slotted shank to lock the knob against removal from the spindle, and means interiorly of the tubular spindle to secure one end of the spring.

3. A device of the character described 60 comprising a tubular spindle, said spindle having a depressed channel formed in one side terminating in a slot at one end and in a perforation at the opposite end, a locking plate slidably mounted and radially movable with relation to the spindle, said locking plate being guided by the slotted portion of the spindle, a spring extending longitudinally through the channel, one end of the spring passing through the perforated 70 end and the other end of the spring exerting an outward pressure on the locking plate to normally project the same, a knob adapted to be received by the spindle, and a shank forming a part of the knob, said shank having a slot formed therein into which the locking plate projects when the knob is in position on the spindle, said plate when projected into the slot securing the 75 knob against movement on the spindle.

WALTER R. SCHLAGE.
